UNITED STATES PATENT OFFICE.

MORTON G. BUNNELL, OF CHICAGO, ILLINOIS, ASSIGNOR TO WESTERN
WHEELED SCRAPER CO., OF AURORA, ILLINOIS.

CRUSHING-MACHINE.

No. 839,103.

Specification of Letters Patent.

Patented Dec. 25, 1906.

Continuation of application Serial No. 9,870, filed March 23, 1900. This application filed October 24, 1900. Serial No. 34,105.

To all whom it may concern:

Be it known that I, MORTON G. BUNNELL, a citizen of the United States of America, and a resident of Chicago, county of Cook, 5 State of Illinois, have invented certain new and useful Improvements in Crushing-Machines, of which the following is a specification.

My invention relates to that particular class of crushing-machines known as "jaw-crushers."

Objects of my invention are to provide a simple, compact, and an easy-running crusher capable of high speed and rapid crushing action and capable of continuous operation with comparatively little wear; to reduce the number of bearing-points, so as to reduce friction, and to avoid the use of certain objectionable features heretofore considered desirable and necessary; to insure certainty 15 of action, particularly when it is found desirable to drive the machine at high speed, and to so distribute the weight and strain as to reduce vibration and danger of breakage, and to provide certain details and features 20 of improvement tending to increase the general efficiency and to render a machine of this character serviceable and comparatively reliable for all kinds of work.

My invention relates to crushing-machines 30 of that particular type in which a crushing-hopper is formed in part by a movable jaw having a pivotal or hinge-like connection, through the medium of a rigid toggle-arm, with a pitman fulcrumed at its upper end 35 upon a swinging yoke and actuated at its lower end by an eccentric device; and in a machine of the above general character an important feature of my invention consists of a movable crushing-jaw having a rigid 40 toggle-arm and of a vertically-disposed pitman having its upper end tied to the swinging yoke and its lower end actuated by an eccentric device, together with means for tying the movable jaw to the portion of the 45 pitman above the eccentric device, and thus keeping the pitman in pivotal engagement with the rear end of said toggle-arm, whereby the said jaw swings or oscillates relatively to the pitman and is also actuated or moved 50 bodily in both directions—that is to say, toward and away from the other jaw of the hopper—by the middle or intermediate portion or by the upper end portion of a pitman 55 fulcrumed at its upper end and actuated at its lower end, which construction, arrange-

ment, and organization of parts and new mode of operation results in permitting practically any degree of speed on the part of a jaw having a movement found to be highly satisfactory and effective and in a consequent improved and highly-efficient crushing action; and another feature of my invention consists in providing a supporting-bearing for the movable jaw, preferably of such character as to leave the jaw free to be raised and 60 in then maintaining the jaw in place upon such bearing during the crushing action by positioning the pivotal or hinge-like connection between the pitman and the toggle-arm at a point on a level, or substantially so, with 65 the upper edge of the crushing-face of the movable jaw, so as to permit the thrust or reaction in the crushing-hopper to be exerted in a direction below or practically below the connection between the jaw and pitman and so that the jaw, although, as stated, 70 being preferably free to be raised, is effectually prevented from jumping up or leaving its bearing while the machine is in operation; and a further feature of my invention 75 consists of a roller or equivalent member interposed between the bottom of the movable jaw and a portion of the body-frame, the said roller or like device thereby constituting 80 both an antifriction supporting-bearing and 85 rolling fulcrum upon which the jaw moves back and forth and tilts or oscillates when actuated by the pitman; and still another feature of my invention consists of the provision of means passing through the middle 90 or intermediate portion of the pitman and connected with the movable jaw in such manner as to keep the pitman in pivotal engagement with the rear end of the toggle-arm, 95 said arm being rigidly connected with the back of the movable jaw, and said means being preferably adjustable for the purpose of taking up wear and lost motion; and another feature of my invention consists in the provision of means for taking up wear between 100 the swinging yoke and the body-frame and between the swinging yoke and the upper end of the pitman, so as to prevent lost motion and permit the machine to be run at any desired speed, and in addition the specific 105 means for tying the movable jaw and pitman together and for tying the ends of the swinging yoke to the body-frame and upper end of the pitman, consisting of U-bolts employed, 110 preferably, in the manner hereinafter ex-

plained, also constitute valuable features of my invention.

In the accompanying drawings, Figure 1 is a plan of a jaw-crusher embodying the principles of my invention. Fig. 2 is a longitudinal section on line X X in Fig. 1. Fig. 3 is a transverse section on line Y Y in Fig. 1. Fig. 4 is a plan of the movable jaw and pitman, the latter being in horizontal section. Fig. 5 is a plan of the rear portion of the yoke, showing the adjacent portion of the pitman in section. Fig. 6 is a plan of the forward portion of the yoke, the adjacent portion of the frame being shown in section. Fig. 7 is a diagrammatic view illustrating different positions of the parts and showing how the roll provides a shifting fulcrum for the jaw.

As thus illustrated, my invention comprises a frame or body A, adapted to provide a stationary support for the various operative parts. The stationary jaw B is rigid with the forward portion of the frame. The movable jaw B' is arranged in opposition to said stationary jaw, and together the two jaws form a hopper for receiving the material to be crushed. A vertically-disposed pitman C, fulcrumed at its upper end and actuated at its lower end by an eccentric D, is arranged in rear of said movable jaw. The toggle-arm B² is rigid with said movable jaw. The rear end of said arm is formed with a cylindric portion B³, extending transversely across the machine and engaging a groove c in the pitman. U-bolts E, extending through the pitman, are employed for holding or binding the jaw and pitman together, it being observed, however, that the joint is of a pivotal or toggle-joint nature. The jaw is preferably supported by an anti-friction-bearing—as, for example, by arranging a roll F between its bottom and the frame. The said roll being interposed between the flat surface b on the jaw and the flat surface a on the frame serves as a sort of shifting fulcrum and supports the jaw for a bodily forward and back vibratory movement practically without friction. As a means for providing a fulcrum for the pitman I connect the upper end of the latter with the frame by means of a swinging yoke G. The cylindric forward portion g of this yoke is journaled in a bearing a' rigid with the frame, and the cylindric rear portion g' of said yoke is seated in a groove c' on the pitman. The yoke and pitman are secured together by U-bolts H, and U-bolts g² are provided for taking up wear, which is only very slight. It will be observed that the jaws are each provided with a removable die and that each die is backed by one or more shims, preferably wedge-shaped in form. The dies and shims can be retained in place by bolts I, having wedge-shaped heads i, the bevel being preferably on the under side, as shown. With this construction the dies can be readily

removed, and by the removal or insertion of shims the distance between the jaws can be varied according to the character desired for the product. The wedge-shaped shims permit the angle of the jaws to be varied according to the character of the rock, ore, or other material to be crushed.

In operation the pitman is reciprocated by the eccentric, and as it is fulcrumed upon the yoke it acts as a lever. The vibratory movement of the pitman operates to alternately thrust the jaw forward and draw it back and to in this way effect the desired crushing action in the hopper. It will be observed that the jaw, although supported by a roll which leaves it free to rise, is held down by the resistance offered by the rock, the lines of resistance passing below the toggle-joint. In this way the jaw is self-controlled and capable of rapid vibration without danger of jumping up or leaving its bearing and practically without friction. It will also be seen that the yoke provides a fulcrum at each stroke of the jaw, the side portions of the yoke with the particular toggle arrangement shown sustaining a tensile strain when the jaw is advanced, and these same side portions being subject to some endwise compressive strain when the jaw is retracted and the movement of the yoke and roll combining to give the jaw a combined bodily forward-and-back and vibratory movement.

It will be readily understood that the bearings for the eccentric shaft can be of any known or approved form and that the machine can be driven by an engine or other suitable power. Even when driven at high speed there is no lost motion and comparatively little vibration, the pivotal connections all being of such character that slight wear can be readily taken up and as to make it unnecessary to employ connections between the movable jaw and body-frame for retracting the jaw and holding the parts together.

With further reference to the antifriction-bearing it will be observed that the roll F is preferably confined between two depending lips on the bottom of the jaw. In this way the roll is prevented from being displaced. Also and as a further advantage of my simplified and improved construction the parts can be readily assembled, and each part can be readily removed for the purpose of repair or substitution.

By referring to Fig. 7 it will be seen that the roll F shifts slightly during the vibration of the jaw. It will also be seen and, as previously stated, that the general trend of the lines of resistance is below the axis about which the jaw swings, or, in other words, that no lines of resistance are liable to occur in such direction as to pass above such axis. In this way or by placing the toggle-joint high, so that all or at least most of the resist-

ince is below such joint, the jaw B', although improvided with means for holding it down, will nevertheless be maintained in firm contact with said roll.

The bearing by which the jaw is supported is, it will be observed, formed by a bar extending between the cheeks of the hopper. The lower end of said jaw is preferably rounded back for the purpose of clearing the throat. In operation the roll rests upon said bearing and supports the jaw and leaves the latter in condition for free and unhindered movement back and forth with relation to said bearing. In this way, as previously described, the jaw is arranged for a vibratory movement practically without friction. Although supported in such manner that it can be instantly raised or removed from its bearing, the jaw is nevertheless maintained in firm contact with its bearing, as the actuating and other movable parts coöperate to hold it down in place upon said bearing. It will also be observed that the swinging yoke is firmly tied at each end—that is to say, that its forward end is secured or tied to the bed or body frame and that its rear end is secured or tied to the upper end of the pitman. It will also be seen that the jaw is firmly tied to said pitman by devices which are adjustable for the purpose of taking up wear, and thereby preventing lost motion. In this way the eccentric and pitman actuate the jaw in both directions, the rear cross-bar of the yoke serving as a fulcrum for the pitman at both the forward and back strokes of the jaw. Thus positively actuated in both directions by the pitman the jaw is made capable of free and unhindered movement back and forth upon a single supporting-bearing. Furthermore, and as previously explained, this arrangement makes it unnecessary to resort to independent devices or means for retracting the jaw. For this reason the eccentric in thus actuating the jaw in both directions will not be subject to uneven wear and will not become flattened. The portion of the pitman above the eccentric does all of the work.

The roll upon which the jaw is supported acts as a rolling fulcrum for the purpose of supporting the jaw in its combined vibratory and bodily forward and back movements. In other words, the movable jaw and its rigid toggle-arm serves as a lever for crushing the rock or ore, the pitman applying the power to such lever at its rear end and the roll serving as a rolling fulcrum upon which this lever is supported. Thus it will be seen that the roll or rolling fulcrum is not only of a character to provide a frictionless bearing for the jaw in its forward and back movements, but also provides a fulcrum upon which the jaw may tilt or rock while it travels back and forth. In this way the roll serves as a rolling fulcrum and antifriction bearing, and it is for this reason that it is

termed a "rolling" fulcrum. The movable jaw and its rigid arm constitute a lever-like crushing member.

With further respect to the desirability and advantage of combining high speed with an effective and satisfactory movement or motion on the part of the jaw without danger of breakage and with a good distribution of the strain and of insuring an effective balance and distribution of the weight of the different parts at any and all times and with any desired speed it will be observed that the pitman is not only subject to the strains incident to employing its middle or intermediate portion or its upper end portion for actuating or bodily moving the movable crushing-jaw in both directions or in all of the directions of its motion, the jaw being connected to swing or oscillate relatively to the pitman, but is also by reason of its being fulcrumed at its upper end and actuated at its lower end subject to the weight or compressive strain imposed upon it by the swinging yoke, the movable crushing-jaw thereby having a pivotal connection with and being actuated bodily in opposite directions or in all necessary directions by that portion of the pitman between its upper or fulcrumed end and its lower or actuated end, or in any event by that portion which is above the eccentric device, thus imposing the entire work of manipulating or operating the toggle-joint and actuating the movable jaw in all of the directions of its motion upon some portion or portions of a pitman which is actuated at a point below such portion or portions and which is fulcrumed at a point above the eccentric device by which it is actuated at its lower end, and as far as the broad feature of employing that portion of the pitman which is above the eccentric device for both manipulating the toggle-joint or pivotal or hinge-like connection between the pitman and movable jaw and actuating said movable jaw in all of the directions of its motion—it being obvious that the said pivotal or hinge-like connection or engagement between the pitman and movable jaw is of a toggle-like character, inasmuch as it constitutes a joint or point of articulation intermediate of the face of the jaw and the fulcrum-point of the pitman—it is obvious that various devices may be employed for connecting or tying the movable jaw to some portion of the pitman above the eccentric device, so as to keep the end of the jaw-arm in pivotal engagement or connection with the said pitman, and for this reason I do not limit myself to the use of U-bolts as the means whereby that portion of the pitman above the eccentric serves to draw the jaw back as well as thrust it forward, as it is obvious that various devices can be employed for this purpose and that the connecting means can be applied to any suitable portion of the movable jaw

without in any way departing from the spirit of my invention.

The arrangement of the point of pivotal engagement or connection between the pitman and the end B³ of the arm of the movable jaw at a point on a level or substantially on a level with the top of the crushing-face of said movable jaw, and considerably nearer the upper end or fulcrum of the pitman than its lower or actuated end regardless of the character of the means for supporting the movable jaw, constitutes an important feature of the invention, as it combines the advantages of preventing any tendency on the part of the movable jaw to rise while acting upon the rock or other material and of a powerful leverage for actuating the jaw by means of a pitman C, which is fulcrumed at its upper end upon a swinging yoke and actuated at its lower end by a suitable eccentric device.

It is obvious that a crushing-machine of this character can be driven by any suitable motive power. In such case the crushing-machine constitutes the connection or medium through and by which the motive power is converted into useful work. It is desirable, consequently, to insure a high degree of efficiency—that is to say, to utilize as much of the power as possible in the real work of exerting a crushing action on the rock. In other words, I aim to reduce the internal resistance, so to speak, of the crushing-machine as much as possible. Therefore I have, as explained, made it one of the principal objects of my invention to so connect and balance the different parts and distribute the weight that the result will be a perfectly harmonious organization and operation and a consequent increase in efficiency.

What I claim as my invention is—

1. A jaw-crusher comprising a bed or body, a hopper formed in part by a movable jaw, a supporting-roll interposed between the bed or frame and the body of the said jaw, a pitman for actuating said jaw and connected with the latter at a point practically or substantially on a level with the top of the jaw, and thereby above or substantially above the lines of resistance, and a swinging yoke having one end tied to the pitman and the other end tied to said bed or frame, said yoke thereby adapted to sustain both tensile and endwise compressive strains during the operation of the crusher, and the roll, yoke and pitman combining to give the jaw a combined oscillatory and bodily forward-and-back movement, the said roll constituting an antifriction supporting-bearing upon and about which the movable jaw is tilted or oscillated by the said pitman.

2. A crushing-machine comprising a movable jaw, a vertically-reciprocating pitman adapted and arranged for actuating said jaw in both directions, said jaw having a rigid

arm swingingly connected at its end to said pitman, a swinging yoke having one end tied to said pitman and the other end tied to the crusher frame or body, so as to provide the pitman with a fulcrum at both forward and back strokes of the jaw, adjustable bearings for taking up wear between the pitman and the jaw and yoke, so as to prevent lost motion, and means for actuating said pitman, the side portions of the yoke thereby adapted to sustain both tensile and endwise compressive strains during the operation of the crushing-machine, and the means for maintaining the connection between the pitman and the said arm being applied to the pitman at a point above the said means for actuating the latter, the point of engagement between the said arm and pitman constituting an axis about which the movable jaw and the pitman have a relative swinging motion.

3. A crushing-machine comprising a suitable bed or body structure, a stationary jaw, a movable jaw, arranged opposite said stationary jaw, a rolling fulcrum upon which said movable jaw rests, a vertically-reciprocating pitman actuated at its lower end by an eccentric, a toggle-arm rigid with said movable jaw and journaled in the pitman at a point substantially on a level with the upper edge of the face of said jaw, and a swinging yoke connecting the upper end of the pitman with the forward end of said bed or body structure.

4. A crushing-machine comprising a suitable bed or body structure, a stationary jaw, a movable jaw arranged opposite said stationary jaw, a vertically-reciprocating pitman actuated at its lower end by an eccentric device, a single bearing for said movable jaw consisting of a rolling fulcrum interposed between the bottom of the jaw and a portion of said bed or body structure, a toggle-arm rigid with said movable jaw and engaging the pitman at a point substantially on a level with the upper edge of the face of said jaw, clips extending through the pitman and binding the toggle-arm and pitman together, a swinging yoke connecting the upper end of the pitman with the forward portion of said bed or body structure, and clips extending through the pitman and binding said yoke and pitman together.

5. A crushing-machine comprising a suitable bed or body structure, a stationary jaw, a movable jaw arranged opposite said stationary jaw, a single bearing for said movable jaw consisting of a roll interposed between the bottom of the jaw and a portion of said bed or body structure, a vertically-reciprocating pitman actuated by an eccentric device, a swinging yoke having one end tied to the upper end of said pitman and the other end tied to the forward portion of said frame or body structure, and a toggle-arm rigid with said movable jaw and connected with

the pitman at a point substantially on a level with the upper edge of the face of the jaw.

6. A crushing-machine comprising a suitable bed or body structure, a stationary jaw, 5 a movable jaw arranged opposite said stationary jaw, a single bearing for said movable jaw consisting of a rolling fulcrum interposed between the bottom of the jaw and a portion of said bed or body structure, a vertically-reciprocating pitman actuated at its lower end by an eccentric, and a toggle-arm rigid with said jaw and pivotally connected with said pitman at a point substantially on a level with the upper edge of the face of said jaw, whereby the pitman and toggle-arm co-operate to prevent the movable jaw from rising from its bearing.

7. A crushing-machine comprising a suitable bed or body structure, a stationary jaw, 20 a movable jaw arranged opposite said stationary jaw, a single supporting-bearing for said movable jaw consisting of a cylindric rolling fulcrum interposed between the bottom of the jaw and said bed or body structure, a vertically-reciprocating pitman actuated at 25 its lower end by an eccentric, and a toggle-arm rigid with said movable jaw and pivotally connected with the upper portion of said pitman.

8. A crushing-machine comprising a suitable bed or body structure, a stationary jaw, 30 a movable jaw arranged opposite said stationary jaw, a single supporting bearing or fulcrum upon which said movable jaw rests, said jaw being left free to be raised, a vertically-reciprocating pitman, an eccentric for actuating said pitman, and a toggle-arm rigid with said jaw, the jaw and arm constituting a lever-like crushing member, and the toggle-arm being pivotally connected with the pitman at a point between the upper and lower ends of the latter, and at a point substantially on a level with the upper edge of the face of said jaw, whereby the pitman 45 and toggle-arm co-operate to maintain the jaw in place upon said fulcrum during the crushing operation.

9. In a crushing-machine, the combination of a suitable body-frame, a jaw rigid 50 with said body-frame, a movable jaw opposed to said stationary jaw and provided with a rigid rearwardly-extending toggle-arm, a vertically-reciprocating pitman actuated at its lower end by an eccentric device, 55 said pitman being provided between its upper and lower ends with a bearing adapted to engage the rear end of said toggle-arm, means for tying the movable jaw and pitman together, said means having a pivotal connection with the toggle-arm and extending through and engaging the back of the pitman above the eccentric device, and a swinging yoke having one end tied to the upper end of said pitman and the other end 60 tied to the body-frame.

10. A crushing-machine comprising a stationary jaw and a movable jaw, a toggle-arm rigid with said movable jaw, a vertically-reciprocating pitman actuated by an eccentric device, said pitman having between 70 its upper and lower ends a point of connection with the rear end of said toggle-arm, means for tying the movable jaw and pitman together and for taking up wear between the pitman and the toggle-arm, said means having a pivotal connection with the toggle-arm and extending through and engaging the back of the pitman above the said eccentric device, a swinging yoke having one end tied to said pitman and the other end tied to the stationary jaw, and suitable devices for taking up wear at each end of said yoke.

11. A crushing-machine comprising a body-frame, a vertically-disposed pitman, a stationary crushing-jaw, a movable jaw supported for bodily movement toward and away from the stationary jaw and provided with a rigid arm pivotally engaging said pitman, an eccentric device for actuating the lower end of said pitman, a swinging yoke 85 having one end tied to the body-frame and the other end tied to the upper portion of said pitman, and means extending through the pitman above the eccentric device to bind the movable jaw and pitman together, 90 whereby the movable jaw swings about its point of pivotal connection with the pitman and is moved bodily in both directions by the middle or intermediate portion of a pitman fulcrumed at its upper end.

12. A crushing-machine comprising a body-frame, a stationary crushing-jaw, a movable crushing-jaw supported for bodily movement toward and away from the stationary jaw and provided with a rigid arm, a pitman fulcrumed at its upper end and actuated at its lower end by an eccentric device, and means extending through and engaging the back of said pitman above the eccentric device, to keep the end of said arm in pivotal engagement with the face of the pitman, whereby the movable jaw swings relatively to said pitman and is actuated in all of the directions of its motion by the portion of the pitman having pivotal connection with the end 105 of said arm.

13. A crushing-machine comprising a body-frame, a stationary jaw, a movable crushing-jaw provided with a rigid arm, a pitman actuated at its lower end, means extending 110 through and engaging the back of said pitman between its upper and lower ends, and at a point above the means for actuating the pitman, to keep the said end of said arm in pivotal engagement with the face of the pitman, 115 a swinging yoke having one end tied to the body-frame, and U-bolts for tying the other end of the yoke to the upper end of the pitman, said bolts extending through the upper portion of the pitman.

14. A crushing-machine comprising a body-frame, a stationary crushing-jaw, a movable crushing-jaw provided with a rigid arm, a swinging yoke, a pitman fulcrumed at its upper portion upon said yoke and actuated at its lower end, and U-bolts for keeping the end of said arm in pivotal engagement with the pitman, said bolts extending horizontally through the pitman above the point at which the latter is actuated, and said yoke having its opposite ends tied respectively to the body-frame and the upper end of the pitman, whereby the said movable crushing-jaw is actuated in all of the directions of its motion by that portion of the pitman which is tied by said U-bolts to the end of said arm. 75
15. A crushing-machine comprising a movable crushing-jaw tied to and having a direct pivotal connection with, and actuated bodily in opposite directions by, a pitman fulcrumed above and actuated at a point below, the jaw thus actuated being adapted to swing relatively to the pitman during the operation of the machine, said pivotal connection or axis about which the jaw and pitman have a relative swinging motion being above the point at which the pitman is actuated. 80
16. A crushing-machine comprising a movable jaw having a direct pivotal engagement with, and actuated in all of the directions of its motion by, a pitman fulcrumed at or near its upper end and actuated at its lower end, the jaw thus actuated being adapted to swing relatively to the pitman during the operation of the machine, said pivotal engagement or axis about which the jaw and pitman have a relative swinging motion being above the point at which the pitman is actuated. 85
17. A crushing-machine comprising a suitable body-frame, a jaw rigid with said body-frame, a movable jaw opposed to said stationary jaw and provided with a rigid rearwardly-extending toggle-arm, a reciprocating pitman actuated at its lower end by an eccentric device, said pitman being provided between its upper and lower ends with a bearing adapted to engage the rear end of said toggle-arm, means for tying the movable jaw and pitman together, said means having a pivotal connection with the movable crushing-jaw and extending through and engaging the back of the pitman above the eccentric device, and a swinging yoke having one end tied to the upper end of said pitman and the other end tied to the body-frame. 90
18. A crushing-machine comprising a movable jaw provided with a rigid rearwardly-extending toggle-arm, a vertically-reciprocating pitman, a suitably-mounted swinging yoke having one end tied to the upper end of said pitman, an eccentric actuating the lower end of said pitman, the said pitman being thereby subject to the endwise compressive strain imposed upon it by the weight of said yoke, the upper portion of the pitman having a pivotal engagement or connection with the rear end of said toggle-arm, and means for tying the movable jaw and pitman together, said means being removably secured to the portion of the pitman above the eccentric device, whereby the said movable jaw swings relatively to the pitman and is actuated in all of the directions of its motion by that portion of the pitman above the said eccentric device. 95
19. A crushing-machine comprising a suitably-supported movable jaw provided with a rigid arm, a swinging yoke, a pitman having its upper end fulcrumed upon the swinging end portion of said yoke, an eccentric device actuating the lower end of said pitman, and means for tying the jaw and pitman together, the end of said arm being held in pivotal engagement or connection with the pitman at a point substantially on a level with the top of the crushing-face of said jaw, whereby, in the main, the crushing action does not tend to lift the jaw, and whereby the said jaw swings relatively to the pitman and is actuated in all of the directions of its motion by that portion of the pitman above the said eccentric device. 100
20. A crushing-machine comprising a suitably-supported movable jaw provided with a rigid arm, a pitman actuated at its lower end by an eccentric device, and a swinging yoke upon which the upper end of the pitman is fulcrumed, the end of said arm having a pivotal engagement or connection with the pitman at a point nearer the latter's upper end than its lower end, and at a point substantially on a level with the top of the crushing-face of said jaw, whereby the said jaw is substantially free from any tendency to rise or swing upwardly about its axis or point of pivotal connection with the pitman during the operation of the machine. 105
21. In a crushing-machine, the combination of crushing means including a pair of jaws, and operating means for producing relative movement between said jaws, said operating means including a pitman, an eccentric for actuating the lower end of said pitman, means including a swinging toggle-arm for directly tying and connecting the upper portion of the pitman to one jaw, a swinging yoke for tying the upper portion of the pitman to the other jaw, the said pitman being adapted to tilt relatively to both of said jaws, and that portion of the pitman above the said eccentric constituting a power-transmitting connection through which all power necessary for producing said relative movement, in all of its directions, is communicated from the eccentric to the crushing means. 110
